[57] **ABSTRACT**

A device for transferring the bobbin of a braiding machine between two adjacent flyer wheels of the type in which a double gripper arm is provided for retaining the bobbin, which double gripper arm has retaining claws which engage behind projections arranged on each of the flyer wheels and in which the longitudinal axis of which gripper arm extends through the axis of the bobbin, in which the surfaces of the retaining claws which engage behind the projections are curved to form a radius which corresponds to the radius of turn of these surfaces about the longitudinal axis of the bobbin, the double gripper arm being rotatable relative to the flyer wheel carrying the bobbin, such that one retaining claw engages with one projection, the rotation effecting the locking or unlocking being controllable such that the transfer region extends across a specific region of the path in advance and after the point of transfer with a uniformly accelerated change in the speed of rotation from the speed of rotation of the transferring flyer wheel to the speed of rotation of the receiving flyer wheel.

DEVICE FOR TRANSFERRING THE BOBBIN OF A BRAIDING MACHINE BETWEEN TWO ADJACENT FLYER WHEELS

The present invention relates to a device for transferring the bobbin of a braiding machine between two adjacent flyer wheels in which a double gripper arm is provided on the bobbin for the purpose of retaining it. The double gripper arm has retaining claws which engage and cooperate with projections arranged on the flyer wheels. The longitudinal axis of which gripper arm also extends through the axis of the bobbin.

In conventional devices, the surfaces of the retaining claws which engage with the projections are curved to form a radius which corresponds to the turn radius of the projections about the axis of the flyer wheels. Furthermore, stops are provided at the point of transfer which effect an abrupt change in the absolute direction of rotation of the bobbin from the direction of rotation of the transferring flyer wheel to the direction of rotation of the receiving flyer wheel, and thereby retain the bobbin in the position required for locking or unlocking. The abrupt engagement of the jaws, however, subjects the separate parts of the device to great mechanical stresses.

A device is also known which prevents the abrupt change in the direction of rotation of the bobbin at the point of transfer. In this device, however, the connecting line of the retaining claws in the form of gripper hooks does not extend through the axis of the bobbin. In addition to a very rapid change in the rotational speed from the rotational speed of the transferring flyer wheel to the rotational speed of the receiving flyer wheel, the aforementioned construction of the double gripper arm requires the bobbin to be additionally accelerated to a rotational speed in excess of that of the receiving flyer wheel, and then to be decelerated. Thus, the separate parts of the device are also subjected to great stresses.

The present invention seeks to avoid the disadvantages of conventional devices, to increase the working speed of the braiding machine and to permit an increase in the size of the braider bobbins.

To solve this problem, a device has been provided in which the surfaces of the retaining claws engaged behind the projections are curved to form a radius which corresponds to the radius of turn of these surfaces about the axis of the bobbin. Moreover, in order to lock the bobbin, the double gripper arm is rotatable relative to the flyer wheel carrying the bobbin, so that one retaining claw engages with one projection. Rotation effecting the locking or unlocking is controllable so that it extends across a specific region of the path in front of and behind the point of transfer with a uniformly accelerated change in the speed of rotation from the speed of rotation of the transferring flyer wheel to the speed of rotation of the receiving flyer wheel.

One advantage of this construction resides in the fact that the angular control movement of the bobbin required for locking or unlocking can be initiated well in advance of the actual point of transfer and can be correspondingly terminated well after the point of transfer. Thus, the mechanical stresses of the bobbin are not greater than the stresses of conventional braiding machines. However, since the centrifugal forces are absorbed directly by the flyer wheels, and the bobbin is accurately guided at all points of the path, the speed of the machine can be substantially increased. Furthermore, it is possible to use larger braiding spools.

It is, therefore, an object according to the present invention to provide a device capable of permitting an increased working speed of the braiding machine and permitting larger size bobbins to be utilized.

It is another object according to the present invention to provide a device for braiding machines which is simple in design, inexpensive in cost and reliable in operation.

Other objects and features of the present invention will become apparent from the following detailed description considered in connection with the accompanying drawings which disclose the embodiments of the invention. It is to be understood, however, that the drawings are designed for the purpose of illustration only and not as a definition of the limits of the invention.

In the drawings, wherein similar reference characters denote similar elements throughout the several views:

FIG. 1 is a diagrammatic section through the part of a braiding machine including flyer wheels, a bobbin, and a device constructed in accordance with the invention;

FIG. 2 is a cross-sectional plan view of the machine of FIG. 1 taken along section 2-2 of FIG. 1;

FIG. 3 is a view taken along section 3-3 of FIG. 1; and

FIG. 4 is a view through the guideway, taken along section 10 4-4 of FIG. 3.

Referring to FIG. 1, flyer wheels 13 and 14 and respective coaxial additional flyer wheels 15 and 16 are arranged adjacent one another above a base plate 10 in axes at right angles to that of base plate 10. The drive for the flyer wheels is effected by way of two gear wheels 11 and 12. Flyer wheels 13, 14 and additional flyer wheels 15, 16 have respective recesses 17 and 18 which, in the bobbin transfer position illustrated, are located exactly opposite one another and surround spindle 19 of bobbin 20. Flyer wheels 13, 14 together with their additional flyer wheels 15, 16 are rotated in opposite directions by the intermeshing of gear wheels 11 and 12. In principle, the locking control is not dependent upon a specific direction in which the braiding machine is running. It operates in the same manner during forward running and reverse running, without 15 additional control elements having to be actuated during changeover.

In the direction of rotation of the flyer wheels illustrated in FIG. 1, bobbin 20 is transferred from left hand flyer wheels 13 and 15 to right hand flyer wheels 14 and 16. During rotation 30 on the path determined by the flyer wheels, a thread is drawn upwardly from a plurality of braiding spool (not illustrated) located on bobbin 20. A plurality of threads may be drawn upwardly from a plurality of braiding spools (not illustrated). Bobbin spindle 19 is retained in recesses 17 and 18 by a locking device, one part of which comprises projections 21 mounted at right angles on flyer wheels 13 and 14, and projections 22 mounted at right angles on upper flyer wheels 15 and 16. The other part of the locking device is formed by a double gripper arm 23 which is arranged on bobbin spindle 19 so as to 35 be non-rotatable relative thereto, and so that two retaining claws 24 and 25, having ends mounted at right angles relative to each other, can engage behind projections 21 and 22. The facing surfaces of retaining claws 24 and 25 are of arcuate configuration having a radius which corresponds to the distance of these surfaces from the center of bobbin spindle 19 with which the double gripper arm 23 rotates. In the illustrated embodiment, the contact surfaces of projections 21 and 22 are also arcuate in order to maintain the contact pressure at a low value.

50 The moving during angular locking will be further described with reference to FIG. 2. During normal rotation around a flyer wheel, the bobbin maintains its position relative to the flyer wheel. As is shown by the broken lines, retaining claw 24 (or 25) is then located centrally behind projection 21 (or 22), and transmits the centrifugal force of the bobbin to the respective flyer wheel.

If one follows the movement of the bobbin corresponding to the direction of rotation of the flyer wheels illustrated in FIG. 2, the rotation of the bobbin corresponding to the speed of rotation of the flyer wheel is decelerated to non-rotation in the first half of the transfer region between points 26 and 27 on the path of movement. The angular acceleration and thus the mechanical stress of bobbin 20 is then, in no way, greater than in conventional braiding machines. This is because the angular position of bobbin 20 is controlled by guide piece 31 which

engages through two followers 32 into guideway 29. Its movements thus correspond to the movement of the bobbin in conventional braiding machines. However, in contrast to bobbin 20, which moves on path 30, guide piece 31 assumes a varying distance from the center of the respective flyer wheel. Thus, its control function is possible only by providing in guide piece 31, a groove 33 which extends transversely to the direction of movement of the guide piece, and engages a sliding block 34 connected to bobbin 20 so as to be non-rotatable relative 65 thereto.

However, to produce the angular movement, it is also possible to couple a rotatable arm to the bobbin which moves relative to the spindle of the bobbin and in the end of which is mounted a guide follower. The follower slides in a guideway which is constructed so that the bobbin carries out the required change in the direction of rotation in the transfer region.

Due to the relative movement between bobbin 20 and the flyer wheel occurring substantially between points 26 and 27 on the path of movement, the longitudinal axis of retaining claw 24 has been turned from the initial radial position in the direction of rotation of the receiving flyer wheel. The pivoted gripper arm, illustrated by solid lines in FIG. 2, shows retaining claw 24 still just in engagement with projection 21, while the oppositely located retaining claw 25 is in engagement with projection 22 which has been reached on the receiving flyer wheel.

When retaining claw 25 reaches projection 22, and retaining claw 24 leaves projection 21 in the vicinity of the point of transition 27, the absolute rotation of the bobbin has stopped. Thus, the same velocity vector can be associated with every point on the double gripper arm. In FIG. 2, these velocity vectors lie at right angles to the connecting line between the axes of the flyer wheels. Their magnitude results from the angular velocity and the size of the pitch circle radius. The velocity vectors of projections 21 and 22 are uniformly directed. However, in conformity with the shorter distance to the respective flyer wheel axis, they are smaller than the velocity vector of the bobbin. Thus, retaining claw 25 can reach projection 22, while retaining claw 24 simultaneously leaves projection 21 behind.

Bobbin 20 is accelerated from non-rotation to the speed of the receiving flyer wheel in the second half of the transfer region between points 27 and 28 on the path of movement. Retaining claw 25 is then turned centrally behind projection 22 by the relative rotation occurring, i.e., the longitudinal axis of double gripper arm 23 again assumes a radial position relative to the receiving flyer wheel. This concludes the reversal of engagement.

The transferring of bobbin 20 from flyer wheel 14 to flyer wheel 13 is effected in a corresponding manner.

While only a single embodiment of the present invention has been shown and described, it will be obvious that many changes and modifications may be made thereunto without departing from the spirit and scope of the invention.

5 What is claimed is:

1. A device for transferring a bobbin mounted on a spindle of a braiding machine between two adjacent flyer wheels comprising;

10 at least one projection disposed on each of said flyer wheels, a double gripper arm for retaining the bobbin, said double gripper arm having retaining claws which engage behind said projections on each of said flyer wheels, the longitudinal axis of said gripper arm extending through the axis of said bobbin, said retaining claws having curved edge surfaces forming a radius corresponding to the radius of the turn of the surfaces about the longitudinal axes of the bobbin, the double gripper arm being rotatable relative to the flyer wheel carrying the bobbin so that one retaining claw engages with one projection for locking and unlocking the flyer wheel such that the transfer region extends across a specific region of the path in advance and after the point of transfer with uniformly accelerated change in the speed of rotation, from the speed of rotation of the transferring flyer wheel to the speed of rotation of the receiving flyer wheel.

20 2. The device as recited in claim 1 additionally comprising a guideway for controlling the rotation effecting locking and unlocking, a guide piece being movable transversely to its direction of movement relative to the bobbin spindle, the rotation of the bobbin spindle being produced by said guide piece connected thereto, and two followers rotatably mounted for sliding one behind the other in the guideway.

25 3. The device as recited in claim 2, wherein one said followers sliding in said guideway produces a rotary movement of the bobbin spindle, wherein the shuttle runs in the guideway deviating from the bobbin path mounted at the end point of a rotary arm connected to the bobbin spindle.

30 4. The device as recited in claim 1, wherein two spaced double-gripper arms are disposed parallel with respect to each other on the bobbin spindle, and additional set of flyer wheels spaced from said original flyer wheels.
